US00D810355S

(12) **United States Design Patent** (10) Patent No.: **US D810,355 S**
 Liu (45) Date of Patent: ** Feb. 13, 2018

(54) **ELECTRONIC CIGARETTE**

(71) Applicant: **HUIZHOU KIMREE TECHNOLOGY CO., LTD**, Huizhou, Guangdong (CN)

(72) Inventor: **Qiuming Liu**, Guangdong (CN)

(73) Assignee: **HUIZHOU KIMREE TECHNOLOGY CO., LTD**, Huizhou, Guangdong (CN)

(**) Term: **15 Years**

(21) Appl. No.: **29/528,414**

(22) Filed: **May 28, 2015**

(30) **Foreign Application Priority Data**

Dec. 19, 2014 (CN) 2014 3 0540343

(51) LOC (11) Cl. **27-01**

(52) U.S. Cl.

USPC **D27/101**

CLAIM

The ornamental embodiment for an electronic cigarette, as shown and described.

DESCRIPTION

FIG. 1 is a front view of an electronic cigarette according to a first embodiment of the present application;
FIG. 2 is a rear view of the electronic cigarette according to the first embodiment of the present application;
FIG. 3 is a left view of the electronic cigarette according to the first embodiment of the present application;
FIG. 4 is a right view of the electronic cigarette according to the first embodiment of the present application;
FIG. 5 is a top view of the electronic cigarette according to the first embodiment of the present application;
FIG. 6 is a bottom view of the electronic cigarette according to the first embodiment of the present application;
FIG. 7 is a first perspective view of the electronic cigarette according to the first embodiment of the present application;
FIG. 8 is a second perspective view of the electronic cigarette according to the first embodiment of the present application;
FIG. 9 is a front view of an electronic cigarette according to a second embodiment of the present application;
FIG. 10 is a rear view of the electronic cigarette according to the second embodiment of the present application;
FIG. 11 is a left view of the electronic cigarette according to the second embodiment of the present application;
FIG. 12 is a right view of the electronic cigarette according to the second embodiment of the present application;
FIG. 13 is a top view of the electronic cigarette according to the second embodiment of the present application;
FIG. 14 is a bottom view of the electronic cigarette according to the second embodiment of the present application;
FIG. 15 is a first perspective view of the electronic cigarette according to the second embodiment of the present application;
FIG. 16 is a second perspective view of the electronic cigarette according to the second embodiment of the present application;
FIG. 17 is a front view of an electronic cigarette according to a third embodiment of the present application;
FIG. 18 is a rear view of the electronic cigarette according to the third embodiment of the present application;
FIG. 19 is a left view of the electronic cigarette according to the third embodiment of the present application;
FIG. 20 is a right view of the electronic cigarette according to the third embodiment of the present application;

FIG. 21 is a top view of the electronic cigarette according to the third embodiment of the present application;
FIG. 22 is a bottom view of the electronic cigarette according to the third embodiment of the present application;
FIG. 23 is a first perspective view of the electronic cigarette according to the third embodiment of the present application;
FIG. 24 is a second perspective view of the electronic cigarette according to the third embodiment of the present application;
FIG. 25 is a front view of an electronic cigarette according to a fourth embodiment of the present application;
FIG. 26 is a rear view of the electronic cigarette according to the fourth embodiment of the present application;
FIG. 27 is a left view of the electronic cigarette according to the fourth embodiment of the present application;
FIG. 28 is a right view of the electronic cigarette according to the fourth embodiment of the present application;
FIG. 29 is a top view of the electronic cigarette according to the fourth embodiment of the present application;
FIG. 30 is a bottom view of the electronic cigarette according to the fourth embodiment of the present application;
FIG. 31 is a first perspective view of the electronic cigarette according to the fourth embodiment of the present application;
FIG. 32 is a second perspective view of the electronic cigarette according to the fourth embodiment of the present application;
FIG. 33 is a front view of an electronic cigarette according to a sixth embodiment of the present application;
FIG. 34 is a rear view of the electronic cigarette according to the sixth embodiment of the present application;
FIG. 35 is a left view of the electronic cigarette according to the sixth embodiment of the present application;
FIG. 36 is a right view of the electronic cigarette according to the sixth embodiment of the present application;
FIG. 37 is a top view of the electronic cigarette according to the sixth embodiment of the present application;
FIG. 38 is a bottom view of the electronic cigarette according to the sixth embodiment of the present application;
FIG. 39 is a first perspective view of the electronic cigarette according to the sixth embodiment of the present application;
FIG. 40 is a second perspective view of the electronic cigarette according to the sixth embodiment of the present application;
FIG. 41 is a front view of an electronic cigarette according to a seventh embodiment of the present application;
FIG. 42 is a rear view of the electronic cigarette according to the seventh embodiment of the present application;
FIG. 43 is a left view of the electronic cigarette according to the seventh embodiment of the present application;
FIG. 44 is a right view of the electronic cigarette according to the seventh embodiment of the present application;
FIG. 45 is a top view of the electronic cigarette according to the seventh embodiment of the present application;
FIG. 46 is a bottom view of the electronic cigarette according to the seventh embodiment of the present application;
FIG. 47 is a first perspective view of the electronic cigarette according to the seventh embodiment of the present application;
FIG. 48 is a second perspective view of the electronic cigarette according to the seventh embodiment of the present application;

FIG. 49 is a front view of an electronic cigarette according to an eighth embodiment of the present application; FIG. 50 is a rear view of the electronic cigarette according to the eighth embodiment of the present application; FIG. 51 is a left view of the electronic cigarette according to the eighth embodiment of the present application; FIG. 52 is a right view of the electronic cigarette according to the eighth embodiment of the present application; FIG. 53 is a top view of the electronic cigarette according to the eighth embodiment of the present application; FIG. 54 is a bottom view of the electronic cigarette according to the eighth embodiment of the present application; FIG. 55 is a first perspective view of the electronic cigarette according to the eighth embodiment of the present application; FIG. 56 is a second perspective view of the electronic cigarette according to the eighth embodiment of the present application;

FIG. 57 is a front view of an electronic cigarette according to a ninth embodiment of the present application; FIG. 58 is a rear view of the electronic cigarette according to the ninth embodiment of the present application; FIG. 59 is a left view of the electronic cigarette according to the ninth embodiment of the present application; FIG. 60 is a right view of the electronic cigarette according to the ninth embodiment of the present application; FIG. 61 is a top view of the electronic cigarette according to the ninth embodiment of the present application; FIG. 62 is a bottom view of the electronic cigarette according to the ninth embodiment of the present application; FIG. 63 is a first perspective view of the electronic cigarette according to the ninth embodiment of the present application; and, FIG. 64 is a second perspective view of the electronic cigarette according to the ninth embodiment of the present application.
